VACUUM BREAKER

William E. Sloan, River Forest, Ill.

Application January 7, 1937, Serial No. 119,440

3 Claims. (Cl. 137—93)

This invention relates to vacuum breakers and has for its object the production of a new and improved vacuum breaker which is more reliable in operation and which is somewhat more sensitive to the discharge of liquid therethrough.

The invention has for a further object to provide a device of the kind described with an air inlet valve having a direct suspension in stable equilibrium from below on a stem affixed to the pivoted arm. This arrangement for suspending the air valve for movement between its open and closed positions permits the valve to hang in a very nearly horizontal plane when in open position so as to offer the least possible restriction to the inflow of air, as well as permitting the valve to line up with the fixed seat so as to seat accurately even though the plane of the seat be tipped in any direction by a substantial amount from the preferred horizontal position. This construction also substantially eliminates any slight possibility of sticking of the parts from corrosion and the like, as well as permitting the air intake portion of the vacuum breaker to be made with a lesser over-all height for a purpose to be subsequently explained.

The invention has for a further object to provide a device of the kind described in which there is a less bulky single-arm suspension of the pivoted arm of the vacuum breaker, in order to provide a still less restricted channel for the intake of air.

The invention has as a further object to provide a vacuum breaker integral with a flush valve, for an integral device can be produced more economically than two separate devices, can be more conveniently handled and can be more compactly installed.

Features of improvement relating to the integral nature of the flush valve and vacuum breaker include the following.

In order for the single unit to be compactly installed it is advantageous for the air inlet portion of the vacuum breaker to be located directly below the inlet opening into the flush valve. When the single unit casting is produced with the parts in this relative position, the height of the bonnet forming the air inlet portion of the vacuum breaker must be reduced as will be hereinafter described, in order that it can be assembled below the water inlet portion of the valve which is integral therewith.

Since the air inlet opening is directly below the casting extension forming the water inlet opening of the flush valve, it is a practical impossibility to thread the air inlet opening for the

reception of the bonnet supporting member, which also forms the seat for the air valve. In order to overcome this difficulty, a somewhat larger opening is made in the casting directly below the air inlet opening, through which larger opening the tool is passed to thread the air inlet opening, following which the larger opening is threaded and is closed with a suitable plug.

Since the vacuum breaker casting is integral 10 with the valve casting, it becomes feasible to roughly cast a seat for the retarder or check valve disc which normally closes the water inlet opening to the vacuum breaker, and to finish this seat by means of a tool passing into the vacuum breaker casting from the outlet opening thereof. When this is done, however, the lug normally provided to prevent the discharge tube from passing so far into the vacuum breaker as to interfere with the working thereof must be limited 15 in length to permit the passage of the finishing tool through the discharge opening. With this limitation imposed on the length of the stop lug, a small diameter discharge tube can be inserted without encountering the stop lug, and would 20 sometimes be inserted so far as to interfere with proper operation of the vacuum breaker parts without special provisions. This possibility is entirely overcome by a novel arrangement which consists in including a stop device for a smaller 25 tube in the adapter which is used to adapt the discharge opening for the insertion of a small discharge tube.

The invention has further objects which are more particularly pointed out in the accompanying description.

Referring now to the drawing, comprising Figs. 1 to 4, they show sufficient views of a combined flush valve and vacuum breaker embodying the features of the invention, to enable the invention to be understood.

Fig. 1 is a vertical sectional view of the integral type flush valve and vacuum breaker;

Fig. 2 is a sectional view taken on line 2—2 of Fig. 1;

Fig. 3 is a stop view of the water receiving disc of Fig. 1, showing the vacuum relieving holes formed therethrough; and

Fig. 4 is a sectional view showing the discharge opening of the vacuum breaker fitted with a pipe of smaller diameter than the discharge opening, but held in place by the combined adapter and limiting stop.

Like numerals refer to like parts throughout the several figures.

This application is a continuation in part of

prior application Serial No. 16,950, filed April 18, 1935.

Referring now to the drawing and particularly to Fig. 1, the casing 1 of the flush valve is preferably a casting and it has integral therewith a vacuum breaker casing 1a. The flush valve casing 1 is provided with a cap member 2 which is threaded into the casing. There is a water inlet 3 threaded to receive a connection to the source of supply. The flush valve casing 1 is connected with the vacuum breaker casing 1a by the outlet opening 4 and the vacuum breaker casing has the discharge opening 5 with which is connected a discharge pipe 5a.

It will be understood that the flush valve shown herein is for the purpose of flushing a closet bowl, a urinal or some other plumbing receptacle to which flushing water is supplied by way of the vacuum breaker through the discharge opening 5, flushing water being received through the inlet opening 3, and that the purpose of the vacuum breaker is to act as a retarder of the back flow of both water and air in the event of a drop of pressure in the supply line below atmospheric pressure, as well as to admit air freely to the interior of the vacuum breaker and thereby prevent water from being syphoned from the receptacle back into the the supply line.

The movable assembly of the flush valve is designated generally by the numeral 6, while the valve seat is designated 7. The flush valve may be of any desired construction, such as that shown in my prior Patent No. 2,016,396, issued October 8, 1935. In the particular construction shown, when the handle 8 is actuated, the actuating member 9 is moved inwardly and engages the stem 10 of an auxiliary valve, relieving the pressure in the chamber above the movable assembly and permitting the valve to be pushed open by the pressure in the supply pipe, whereupon water flows through the flush valve until the valve closes, after the auxiliary relief valve thereof has seated to permit the pressure to be built up in the control chamber above the moving assembly to again seat the assembly on the seat 7. The flow of water which takes place during the time the flush valve is open is utilized to flush the associated receptacle, and brings into operation the vacuum breaker.

Referring now particularly to the vacuum breaker portion of the disclosure, the air valve is indicated generally by the numeral 11, while the water receiving or retarding member which retards the back flow of air and water is indicated at 12. These two devices are supported on the pivoted arm 13, which in turn is pivoted on the pins 14 and 15, as shown best in Fig. 2.

The air valve 11 is composed of the central hollow stud 19, which is provided with a shoulder against which the metal washer 20 lies to hold the metal reinforced seating washer 21 firmly in place against the weight member 22, the entire assembly being held together by virtue of the threaded connection between the hollow stud 19 and the weighted member 22. The member 22 is provided with sufficient thickness that its weight is sufficient to overbalance the weight of the opposite end of the arm and cause the device to be held by gravity in the normal position shown in the drawing, in which position the retarding member 12 lies snugly against the seat formed around the lower part of the orifice 4, which serves as an outlet for the flush valve and as an inlet for the vacuum breaker. The bonnet

supporting casting 16, which supports the protecting bonnet 18, has a machined seat with which the seating member 21 cooperates to seal the air inlet opening when the vacuum breaker 5 is actuated to its alternate position during the flow of water through the vacuum breaker. The casting 16 has a large opening therethrough, through which air may enter after passing below the edge of the bonnet 18. The bonnet 18 is supported by a relatively slender bridge which is integral with the casting 16 and which is secured at diametrically opposite edges to the casting.

Since the casting does not guide the air valve, the casting and bonnet may be made shorter and more compact to enable the assembly to be introduced under the inlet extension 3.

In order to support and guide the air valve 11 from within the body of the vacuum breaker, so as to enable the over all height of the air inlet portion to be kept to a minimum, as well as to provide an air valve which will operate with a minimum of friction and seat accurately, the support member 13 is provided with an integral stud 23 which enters the hollow stud 19 of the air valve 11 and supports the air valve on the rounded end of the stud 23.

The pivot point of the lever 13 is preferably substantially on a line between the fixed seating surfaces of the air inlet valve and the retarder, in order that the thrusts be directed at substantially maximum leverage. With the location of the pivot point thus fixed, it is necessary to lower the lever arm proper considerably below the pivot point in order to allow room for supporting the air valve and the retarder disc for substantial movement. For this purpose, the pivoted lever 13 is provided with a portion uprising therefrom which ends in the part thereof which is pivoted by the pins 14 and 15, as shown best in Fig. 2. The lever, therefore, comprises two members lying at right angles to one another and connected together by the vertically extending connecting portion, one of these members being the axial, hollow pivot member, while the other is the member which supports the air valve and the retarding member.

The retarder member 12 has a depending stem 24 which passes through a flared hole in the enlarged end of the lever arm 13. As may be seen in Fig. 3, the member 12 is provided with a plurality of relatively small holes through which a small amount of air may be drawn, under the condition of subatmospheric supply pressure, to relieve the syphon condition and thereby prevent injurious water hammer in the event that normal supply pressure is suddenly restored. Without this provision, the water, on dropping entirely out of the upper end of a long vertical riser, may leave a substantial vacuum into which the water can rush uncushioned upon the restoration of pressure.

Since the air inlet opening to the vacuum breaker in which the bonnet support 16 is threaded lies directly below and in line with the water inlet opening 3 of the casting, the water inlet extension is so located as to make it a practical impossibility to drill and thread the air inlet opening from above. To meet this condition, a working opening in the bottom of the vacuum breaker is made directly below the air inlet opening, through which the air inlet opening can be threaded. This working opening is made somewhat larger than the air inlet opening for this purpose, and is subsequently

threaded and closed by the plug 25, provided with a sunken portion to enable it to be turned into place by a suitable tool.

In operation, when water discharged from the flush valve starts to flow through the vacuum breaker on its way to the receptacle, the action of the water on the retarding member 12 moves this member downwardly, rotating the lever arm 13 in a counter-clockwise direction, as seen in Fig. 1, to the limit of its movement, the water impinging upon and being diverted by the retarder member 12. It is to be noted that the body of the vacuum breaker is substantially larger than the member 12 so as to allow the water to flow around the member after striking it. The movable part of the vacuum breaker is thereby kept in actuated position as long as any substantial flow is taking place, as the over-balance of the parts in favor of the normal position is relatively slight, and complete advantage is taken of the pushing effect of the water striking against the member 12.

When the discharge flow starts as previously mentioned and the pivoted arm 13 is caused to assume its alternate position, the valve 11 is brought against the seat, which is preferably machined, at the lower end of the casing 16, the contact between this seat and the seating member 21 completely closing the air inlet opening. It is to be noted that the point of contact between the end of the stud 23 and the end of the blind hole in the hollow stud 19 of the air valve is now within the casting 16, and above and beyond the seating surface. This arrangement enables the valve 11 to be accurately and practically frictionlessly aligned with the fixed seat, which is not the case when the support point is on the other side of the air valve. In the arrangement shown, the air valve is in effect pulled shut by virtue of the location of the point of contact between it and the stud 23, as contrasted with being pushed shut if the air valve is supported from below. This arrangement, it will be understood is of particular utility in a vacuum breaker, for the amount of thrust available for the closing of the air valve is somewhat limited. Moreover, the air valve must close reliably in order to prevent the undesirable spilling of water through the air inlet opening.

In the event that the opening into the receptacle is small or becomes partly clogged, causing a pressure greater than atmospheric pressure to build up, such augmented pressure acts against the bottom of the air valve 11 and thereby aids in maintaining the air valve securely seated against the escape of water.

When the flush valve closes, and the flow of water therefore ceases, the lever of the vacuum breaker is free to be propelled by gravity to its normal position, for the air valve 11 is sufficiently heavy to overbalance the weight on the opposite end of the lever. Moreover, the air valve 11 is vigorously unseated at this time by the outside atmospheric pressure working against the sub-atmospheric pressure which develops upon the closing of the valve and results from the weight of the column of water between the vacuum breaker and the receptacle.

At this point it is to be noted that the blind hole in the hollow stud 19 of the air valve is flared out so as to allow the air valve to hang more nearly horizontal in the normal position of the device, as well as to insure complete freedom of the air valve in aligning itself upon its seat, even in the face of any adverse incrustation

which may conceivably form on the inner surface of the blind hole in the stud 19.

As previously mentioned, the machining of a seat for the retarding member 12 against the portion of the casting defining the common orifice 4, is of necessity accomplished through the discharge opening 5 at the lower end of the casting. In order that the tool for performing this machining can be inserted and withdrawn, it is necessary that the length of the limiting stud 29 be kept to a minimum (just sufficient to prevent a tube of normal diameter from being pushed in beyond the stud). This consideration does not apply, of course, when the vacuum breaker is produced separately from the valve, this problem being present only when the vacuum breaker and the flush valve make use of an integral casting. In order to overcome this difficulty, a combined adapter and stop for a tube of smaller diameter has been developed, as illustrated in Fig. 4.

In Fig. 4, the outlet opening 5 of the casting 1 is provided with a discharge tube 30 of smaller diameter than the discharge tube 5a of Fig. 1, and this smaller pipe is held snugly in place and is prevented from being inserted too far into the casting by the combined adapter and stop 31. This combination unit is composed of a metallic element 32 and a molded rubber element 33, the rubber being vulcanized to the metal element to form a single unit. The metal element 32 is substantially a short tube with the lower end thereof brought out to form a horizontal ledge all around the main body of the tube, while the upper end of the tube is drawn in to form an internal ledge which serves to limit the tube 30 from being pushed so far within the casting that it interferes with the operation of the vacuum breaker.

The rubber portion 33 is molded within the tubular portion of the element 32 and is of such internal diameter as to allow the tube 30 to fit snugly. In addition, the rubber portion 33 follows around the bottom ledge of the member 32 so as to form a continuous water-tight sealing gasket. When the clamp nut 38 is drawn into place, the gasket portion of the rubber element 33 is constricted vertically and thereby caused to expand horizontally in the usual manner to hold the tube 30 firmly in place and to seal the outlet against the loss of water.

I claim:

1. A seating member for a valve, comprising a main disc, a clamping disc, and a seating disc of resilient material disposed between the first mentioned discs, each of said discs having a central hole therethrough, and a clamping stud extending through said holes to hold the discs together, said clamping disc being smaller in diameter than said seating disc so as to leave an annular seating surface exposed on one side of the seating disc, there being a blind hole formed longitudinally in the clamping stud entering the end thereof from the non-seating side of the assembly and ending substantially beyond the said exposed seating surface of the seating disc.

2. In a vacuum breaker including a relief valve and a retarder disc mounted on opposite ends of a pivoted lever, a fixed seating surface for the retarder disc and a fixed seating surface for the relief valve in substantial alignment with one another, the pivot point for said lever being located substantially in the same plane as the said seating surfaces, said lever comprising a horizontal pivot member disposed substantially at right angles to a line passing through the centers of the two seating surfaces, a horizontal lever member

lying below the pivot member and at right angles thereto, and a vertical member connecting the horizontal members together to form a unitary structure.

3. In a flush valve and a vacuum breaker occupying a unitary casing which has one portion for the flush valve and another portion for the vacuum breaker, said casing having an extension with an inlet opening therein for the reception of liquid, the vacuum breaker portion of the casing having a vertical threaded air-inlet opening located below and obstructed by the inlet exten-

sion of the casing, the method of threading the air inlet opening of the vacuum breaker portion of the casing which includes providing a working opening in the casing on the opposite side of the air inlet opening from the liquid inlet opening, in forming the threads in the air inlet opening by means of a threading tool passing through the working opening, and in closing the working opening after the threading operation has been completed.

WILLIAM E. SLOAN.
